UNITED STATES PATENT OFFICE.

JOSEPH L. DUGGAN, OF CHESTER, PENNSYLVANIA.

GAME.

1,353,462.

Specification of Letters Patent. Patented Sept. 21, 1920.

Application filed November 14, 1919. Serial No. 337,929.

To all whom it may concern:

Be it known that I, JOSEPH L. DUGGAN, a citizen of the United States, residing at Chester, in the county of Delaware and State of Pennsylvania, have invented certain new and useful Improvements in Games, of which the following is a specification.

This invention relates to games. It is designed to provide a toy adapted to interest the player and at the same time to develop skill in the use of the hand and rapidity of adjustment in the use of the eye. It is designed to be held in the hand while in use and by its tipping in any desired direction to cause a series of balls to roll over a play field and through gates or openings into an inclosure in which a larger ball is placed.

20 In the drawings herewith accompanying and making a part of this application, Figure 1 is a plan view of the game and Fig. 2 is a sectional view of a portion thereof showing the structure of the gate staples and the transparent top.

The same reference characters indicate like parts in the several figures.

In said drawings, 1 is a container having a play field 2, and upturned sides 3. Mounted in the play field are a series of gate staples 4 which are horizontally bent, as seen in Fig. 1, and form an inclosure 4^a. They are provided with points 5 which are inserted in the play field. The adjacent ends of the staples are spaced apart forming openings 6, as seen in Fig. 1. The number of staples in the series shown is six, but the number may vary. Located in the inclosure 4^a is another series of similar staples 4^b forming an inclosure 7^a. This inner series is of a smaller number than the outer series. The openings between staples of the inner series diverge, while those between the staples of the outer series converge.

45 The game is played with one large ball 8 and a series of smaller balls 9. In play, the large ball 8 is placed inside inclosure 4^a and the size of this ball is somewhat larger than the openings 6. The game may be to tip the container to cause the balls 9, all of them, to enter through openings 6 into inclosure 4^a. The larger ball 8 aids in accomplishing this result by temporarily, at least, closing one

of the openings 6. The game may also be to cause the balls 9, when in inclosure 4^a, to gather in one of the openings 6 around ball 8, as seen in dotted lines in Fig. 1. Of course the number of balls 9 may vary at will. The container is closed with a transparent cover 10. The distance between cover 10 and the play field relative to the staples 4 is such that the ball 8 cannot escape from the field inclosed by staples 4.

I claim:

1. In a game, a container, a series of longitudinally bent staples arranged on a field to form a substantially circular inclosure, a relatively large ball in said inclosure, said staples being spaced apart and forming inclined openings into said inclosure and a series of small balls to be brought into said inclosure.

2. In a game, a container having a play field, a series of horizontally bent staples mounted in the play field to form a substantially circular inclosure, the staples being spaced apart from each other and forming outwardly converging openings between adjacent staples, a relatively large ball mounted in said inclosure and larger than said openings and a plurality of small balls smaller than said openings.

3. In a game, a container having a transparent cover, a play field at the bottom of said container, a series of horizontally bent staples mounted in said play field and forming an inclosure, adjacent staples being spaced apart forming outwardly converging openings, a series of similarly bent staples centrally located and forming an inner inclosure, adjacent staples being spaced apart forming outwardly diverging openings, a ball positioned in said outer inclosure and somewhat larger than said openings and a plurality of smaller balls adapted to pass freely into and out of said inclosure.

4. In a game, a container having a transparent cover, a series of horizontally bent staples placed apart, forming converging openings between adjacent staples, a ball too large to pass between said adjacent staples or between the transparent cover and the top of said staples and a series of smaller balls adapted to pass freely into and out of said inclosure.

JOSEPH L. DUGGAN.
